UNITED STATES PATENT OFFICE.

CLARENCE D. PLATT, OF BRIDGEPORT, CONNECTICUT.

ELECTRICAL RECEPTACLE.

1,271,217

Specification of Letters Patent. Patented July 2, 1918.

Original application filed February 15, 1917, Serial No. 148,785. Patent No. 1,231,063. Divided and this application filed June 9, 1917, Serial No. 173,699.

To all whom it may concern:

Be it known that I, CLARENCE D. PLATT, a citizen of the United States of America, residing at Bridgeport, Connecticut, have invented a new and useful Electrical Receptacle, of which the following is a specification.

The main object of my invention is to facilitate the connection of the circuit wires to the terminals or binding posts so that it will be unnecessary to cut the wires for the purpose of attachment.

This object is attained by a special construction of the body of the receptacle and the relation of the terminals thereto.

Figure 1 is a side view of a receptacle embodying the improvements of my invention mounted in an outlet box and with a cover plate shown in section.

Fig. 2 is a front view of the same with the cover plate removed.

Fig. 3 is a front view of the receptacle with the metal parts removed.

Fig. 4 is a rear view of the receptacle.

Fig. 5 is a longitudinal sectional view of the receptacle.

The main body 6 of the receptacle is preferably formed of an insulating material and of a shape and size appropriate to the mechanism to be contained therein. In this case there is a screw socket 7 and a center contact 8 for a fuse plug or a lamp base. The details of the interior construction are more fully described in my Patent #1,231,063, from which this case is a division.

The receptacle is adapted to be mounted in an outlet box 9 of the usual type. The ends 10 of the receptacle are constructed to support the anchor members 11 which are secured thereto by screws such as 12. The anchor members are adapted to be secured to the box body by screws such as 13. The cover plate 14 is adapted to be secured to the receptacle by screws such as 14' which engage in the anchor members 11.

The body is provided with an integral insulating lug 15 at one side of each end forming an extended seat for the terminal plate 16 which is secured in place by a screw

17. Grooves 18 and 19 are formed on opposite sides of each of the lugs 15 to afford passages extending from front to rear for the conducting wires. This enables a conductor to be looped as shown at 20 in Figs. 55 1 and 2 over the lug, the central part 21 of the wire being bared and gripped under the head of the binding screw 22, the two legs of the loop lying in the grooves 18 and 19. By this construction it is unnecessary to 60 sever the wire and it is possible to obtain a strong connection which will sustain a strong pull on the conductor without breaking the connection.

I claim:

1. In a receptacle of the character described, an insulating base having a projecting terminal seat extended beyond the general outline of said base and rearwardly extending wire-receiving grooves at each 70 side of said projecting terminal seat to thereby provide a projection over which a wire may be looped from the rear of the base and laid in the grooves at opposite sides of said projection, and a terminal on 75 the face of the projecting terminal seat for securing the wire looped thereover.

2. In a receptacle of the character described, a base of insulating material having a central body portion with an extended 80 end portion narrower than said central body portion and a projecting terminal seat at one side of and spaced away from the narrowed end portion, whereby to provide wire-receiving grooves at each side of said projecting terminal seat and a terminal on the 85 face of said projecting terminal seat intermediate said wire-receiving grooves.

3. In a device of the character described, a base of insulating material having a projecting terminal seat near one end, a terminal mounted on said seat, a binding screw in the terminal and grooves in the sides of the base on opposite sides of said projecting terminal seat whereby attaching wires may 95 be looped over the terminal on the projecting terminal seat from the back of the base and through the grooves in the base.

4. In a receptacle of the character described, an insulating base having a project-

2
ing terminal seat extended beyond the general outline of said base and rearwardly extending wire-receiving grooves at each side of said projecting terminal seat to thereby provide a projection over which a wire may be looped from the rear of the base and laid in the grooves at opposite sides of said pro-

jection, a terminal on the face of the projecting terminal seat for securing the wire looped thereover and supporting members 10 secured to the insulating base and projecting beyond the ends of the same for securing the receptacle in a wall box or the like.

CLARENCE D. PLATT.
